UNITED STATES PATENT OFFICE

ERNST KOBEL, OF ENNETBADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND

EVACUATING PUMP

Application filed August 19, 1929, Serial No. 386,755, and in Germany August 27, 1928.

This invention relates to improvements in evacuating pumps and particularly to static pumps operating by diffusion of the fluids to be withdrawn from a chamber into a vapor created in the pump.

5 A fluid may be withdrawn from a chamber by causing the fluid to mingle with a vaporized substance flowing away from an orifice in such chamber and by causing the mixture of fluid and vapor to flow into a space wherein the temperature relations are such that the vaporized substance will be condensed, thereby releasing the fluid mixed therewith and permitting such fluid to escape while the presently condensed and previously vaporized substance is returned to its source.

10 The velocity of a molecule of vapor is greatest at that portion of its path which is substantially in the direction of flow of the greater portion of the molecules which portion of the molecular path is nearest the point of separation of the molecules from the mass. If, therefore, the gases to be withdrawn from a chamber are drawn into an evacuating pump, operating on the diffusion principle, at that portion of the path which has the greatest molecular velocity, the amount of kinetic energy available 15 for producing mixture of the fluids and the vapor is at the maximum and the pump will operate at the highest efficiency. Metallic vapor pumps have been so constructed heretofore that the fluids to be withdrawn from

20 a chamber were discharged at some point in the path of flow of the vapor in the pump. Such constructions, however, do not fully utilize the kinetic energy of the vapor so that the efficiency of the pumps and the degree of evacuation attainable by the use of such pumps is limited by the degree of utilization of such kinetic energy.

25 It is, therefore, among the objects of the present invention to provide an evacuating pump operating on the diffusion principle

in which the kinetic energy of the vapor within the pump is utilized as completely as possible.

Another object of the present invention is to provide a static evacuating pump in which the fluids to be withdrawn from a chamber to be evacuated are delivered into the pump below the surface of the substance forming the source of the evacuating vapor.

30 A further object of the invention is to provide a static evacuating pump in which the fluids to be evacuated from a chamber are delivered into the pump chamber at a point below that at which the molecular movement of the vapor is at its maximum.

35 Objects and advantages, other than those above set forth, will be apparent from the following description and the drawing which shows, partially in cross section, an exemplary embodiment of the invention.

40 Referring more particularly to the drawing by characters of reference, reference numeral 1 indicates the side walls of a pump chamber which is formed with double walled portions 2 for the purpose of providing a space through which a cooling medium may be circulated. The operating chamber of the pump is closed by a top member 3 having a conduit 4, connected therewith for attachment to a preliminary evacuating pump (not shown). A convex deflector 6 is attached in spaced relation to top 3 in front of the entrance into conduit 4 for a purpose which will appear hereinafter.

45 A false bottom 7, preferably integral with the side walls 1 of the pump, extends between the side walls in such position and in such manner that the side walls extend downwardly to form a space which is entirely inclosed by a true bottom 8. The false bottom 7 is pierced at a plurality of points and is provided with a plurality of nozzles 9 of such height as to extend to just beyond the upper surface of a layer 11 of vaporizable material such as

mercury. The nozzles may be uniformly or non-uniformly arranged with respect to the area of the false bottom as may appear desirable to secure the maximum utilization of the molecular energy.

- 5 A connection 12 with the chamber to be evacuated (not shown) is provided with a double walled portion 13 through which a cooling medium may be circulated for the 10 purpose of cooling and thereby condensing the fluids to be evacuated. The connection 12 discharges into the space between false bottom 7 and true bottom 8, hereinafter called the receiving space, through a conduit 14 which extends into connection 12 for a short distance above the bottom 16 to form a trap for any condensed fluids entering the cooled connection 12. The connection 12 to the chamber to be evacuated is 15 preferably also provided with a connection 17 discharging into the pump chamber below the surface of the layer of mercury therein in case the chamber to be evacuated contains vaporized mercury. Double walled 20 portions 2 and 13 may be connected as shown to provide for a continuous circulation of cooling medium, such as water, therethrough. Heating means such as coils of tubing 18 arranged within the mercury 25 layer 11 and provided with a circulating heating medium, or a similarly arranged resistance for electrical heating, provide the heat necessary for vaporizing the mercury to obtain a rising molecular flow therefrom.
- 30 35 When a space is to be evacuated, the mercury layer 11 is heated so that a portion thereof is vaporized and the vapor rises from the upper surfaces of the mercury layer into the upper portion of the main 40 chamber of the pump. The gases present in the receiving space between the true and false bottoms are withdrawn therefrom through the nozzles by a jet action, and are diffused through the vapor rising in the 45 pump chamber, with great speed and ease for the reason that the nozzles discharge into the main chamber of the pump at points at which the velocity of the vaporized mercury is greatest. The temperature of gases 50 flowing from the chamber to be evacuated is reduced by cooling in the connection 12, by contact with the cooled walls thereof, so that the gases are somewhat condensed and are allowed to flow into the receiving space 55 at a relatively high vapor density. As soon as the gases have been withdrawn from the space and diffused through the vapor arising from the layer of mercury, they are carried upwardly through the main operating chamber into contact with the cooled walls thereof whereupon the metallic vapor is condensed and allowed to return to the 60 bottom and the gases released therefrom are withdrawn from the operating chamber by 65

a preliminary evacuating pump connected to the discharge conduit.

Although but one embodiment of the invention has been illustrated and described, it will be understood that various other embodiments are possible, and that various changes may be made without departing from the spirit of the invention or the scope of the claims.

The invention claimed is:

1. In a pump for obtaining a high vacuum, an operating chamber having a space formed therebeneath for receiving fluids from a container to be evacuated, nozzles connecting said operating chamber with the receiving space, a quantity of vaporizable material within said chamber, said nozzles discharging adjacent the upper surface of said vaporizable material, and means for heating said material to cause vaporization thereof.

2. In a pump for evacuating gases from a vessel, an operating chamber, a receiving chamber formed adjacent said operating chamber for connection with the vessel to be evacuated, vaporizable material within said operating chamber, means for heating said material to cause vaporization thereof, and a plurality of nozzles for connecting said receiving and said operating chambers and permitting gases to flow therethrough, said nozzles discharging into said operating chamber at the point of the greatest velocity of the molecules freed by vaporization of said material therein.

3. In a pump for evacuating gases from a vessel, an operating chamber, a receiving chamber formed adjacent said operating chamber for connection with the vessel to be evacuated, vaporizable material within said operating chamber, means for heating said material to cause vaporization thereof, and a plurality of nozzles for connecting said receiving and said operating chambers and permitting gases to flow therethrough, said nozzles discharging the gases to be evacuated at the point within said operating chamber at which the vapor generated therein is substantially free from gases.

4. In a pump for evacuating gases from a vessel, an operating chamber, a receiving chamber beneath said operating chamber for connection with the vessel to be evacuated, vaporizable material within said operating chamber, means for heating said material to cause vaporization thereof, and a plurality of nozzles extending upwardly from said receiving chamber into said operating chamber and extending through said vaporizable material in the latter, said nozzles discharging the gases to be evacuated directly above the surface of said vaporizable material in said operating chamber.

5. In a pump for evacuating gases from a vessel, an operating chamber, a receiving

chamber formed adjacent said operating chamber for connection with the vessel to be evacuated, vaporizable material within said operating chamber, means for heating said material to cause vaporization thereof, and a plurality of nozzles connecting said receiving and said operating chambers, and permitting gases to flow therethrough, said nozzles being so arranged as to discharge 10 the gases to be evacuated substantially uniformly into the bottom of said operating chamber directly above the surface of said vaporizable material.

In testimony whereof I have hereunto 15 subscribed my name this 2nd day of August, A. D. 1929.

ERNST KOBEL.
